Primary Examiner — Karen E Eldridge Powers(74) *Attorney, Agent, or Firm* — Myers Wolin, LLC(57) **CLAIM**

The ornamental design for a brush handle, as shown and described.

DESCRIPTION

FIG. 1 is a perspective view of a brush handle showing my new design;

FIG. 2 is a side elevation view thereof;

FIG. 3 is an enlarged side elevation view taken along circle 3 in FIG. 2;

FIG. 4 is an enlarged section taken along line 4-4 in FIG. 3; and,

FIG. 5 is an enlarged section taken along line 5-5 in FIG. 3. The broken lines illustrate the bounds of the claim as well as the bounds of the enlarged views, and indicate where the enlarged views were taken. None of the broken line subject matter forms part of the claimed design. Further, the broken away symbols (the brackets) in the drawings indicate that any portion of the article beyond what is shown forms no part of the claimed design.
